(57) **CLAIM**

The ornamental design for a kitchen garden cabinet, as shown and described.

DESCRIPTION

FIG. 1 is a perspective view of an embodiment of a kitchen garden cabinet with two transparent or translucent front portions ;

FIG. 2 is a front elevation thereof;

FIG. 3 is a right side elevation thereof;

FIG. 4 is a left side elevation view thereof;

FIG. 5 is a top plan view thereof;

FIG. 6 is a bottom plan view thereof; and

FIG. 7 is a bottom perspective view thereof.

FIG. 8 is a perspective view of another embodiment of a kitchen garden cabinet with two transparent or translucent front portions;

FIG. 9 is a front elevation thereof;

FIG. 10 is a right side elevation thereof;

FIG. 11 is a left side elevation view thereof;

FIG. 12 is a top plan view thereof;

FIG. 13 is a bottom plan view thereof; and

FIG. 14 is a bottom perspective view thereof.

FIG. 15 is a perspective view of another embodiment of a kitchen garden cabinet with two transparent or translucent front portions;

FIG. 16 is a front elevation thereof;

FIG. 17 is a right side elevation thereof;

FIG. 18 is a left side elevation view thereof;

FIG. 19 is a top plan view thereof;

FIG. 20 is a bottom plan view thereof; and,

FIG. 21 is a bottom perspective view thereof.

Broken lines in the drawings are for the purpose of illustrating portions of the article that form no part of the claimed design. No claim is made to the rear view/ back side views of any embodiment, none of which are illustrated herein.

1 Claim, 15 Drawing Sheets
